UNITED STATES PATENT OFFICE.

WILHELM A. ZICKERMAN, OF HYDE PARK, MASSACHUSETTS, ASSIGNOR, BY
MESNE ASSIGNMENTS, OF ONE-HALF TO OLONDO B. EMERY.

CUSHION-HEEL.

SPECIFICATION forming part of Letters Patent No. 634,435, dated October 3, 1899.

Application filed May 24, 1899. Serial No. 718,112. (No model.)

To all whom it may concern:

Be it known that I, WILHELM A. ZICKERMAN, of Hyde Park, county of Norfolk, State of Massachusetts, have invented an Improvement in Cushion-Heels, of which the following description, in connection with the accompanying drawings, is a specification, like letters and figures on the drawings representing like parts.

10 This invention has for its object the production of a cushioned elastic heel for boots and shoes, whereby in addition to the elasticity and resiliency of the material of the heel an air-cushion contained therein will increase the springiness of the heel and add to the comfort and ease of the wearer.

Various novel features of my invention will be hereinafter described, and particularly pointed out in the claims.

20 Figure 1 is a longitudinal sectional view of a heel embodying my invention on the line xx , Fig. 2, attached to a boot or shoe heel. Fig. 2 is an underside or face view of the cushion-heel; and Fig. 3 is a top or plan view thereof, showing the chamber therein which forms the air-cushion when the heel is secured in place.

In carrying out my invention I make the heel preferably of homogeneous elastic material, such as rubber, molded to shape and vulcanized, the heel comprising a body portion a of the external shape and size of the boot or shoe heel or heel-lifts H , Fig. 1, to which it is to be secured, said body having a 30 recess or chamber a' in its top and a projecting tread portion a^2 on its face. The chamber a' is shaped similarly to the perimeter of the body a to present a rather broad, smooth, and flat rib-like attaching-surface a^x , Fig. 3, which in practice is cemented, as at c , Fig. 1, to the heel of the boot or shoe, thus confining a body of air in the chamber a' . The tread portion a^2 , projecting from the face of the body a , is of substantially the shape and size of the chamber and below the latter, the face of said tread portion being corrugated or otherwise roughened, as at a^3 , to afford a firm hold on the ground or other surface walked upon.

40 When the weight of the user is brought

upon the heel, the resiliency of the material thereof takes up shock or jar; but in addition the tread portion a^2 is forced upward, compressing the air contained in the chamber a' , the elasticity of the air-cushion thus 55 formed adding to the elasticity and resilience of the material of which the heel is made.

In order to avoid a thin joint or hinge between the body a of the heel and the projecting tread portion, I make the side walls of the 60 chamber merge into the bottom thereof in a curve, as shown at 10, Fig. 1, and likewise the sides of the tread portion merge into the body in a curved surface, as at 20, so that the portion of the material between such 65 oppositely-curved surfaces is thick and strong enough to resist the constant movement of the tread portion up and down relatively to the body of the heel.

The heel herein shown is secured to the heel 70 of the boot or shoe by cement, as at c , Fig. 1, and preferably by nails or other fastenings d , extended through the laterally-projecting part of the body a into the boot or shoe heel.

I prefer to make the heel of homogeneous 75 molded rubber, because of the greater durability and resilience thereof and on account of cheapness of construction, and, referring to Fig. 1, it will be seen that the tread portion a^2 may be worn down level with the face 80 of the body a without destroying the integrity of the air-chamber, as the depth of the chamber is made about one-half that of the thickness of the body irrespective of the thickness of the tread portion. 85

My invention is not restricted to the precise construction and arrangement shown, and I have only shown and described one practical embodiment of my invention without attempting to illustrate various modifications coming within the spirit and scope of my invention. 90

Having described my invention, what I claim as new, and desire to secure by Letters Patent, is—

1. As an article of manufacture, an elastic heel for boots and shoes, having an integral tread portion projecting from the face of the solid body portion of the heel, and a chamber in the heel above said tread portion. 100

2. As an article of manufacture, an elastic heel for boots and shoes, having a recessed top adapted to be cemented at its edges to a heel-lift, and a tread portion projecting from the face of the heel.
5. 3. As an article of manufacture, an elastic heel for boots and shoes, comprising a body portion chambered in its top and with a tread portion projecting from its face, the side walls 10 of the chamber and tread portion being oppositely curved to provide a thick portion of the elastic material between them.
15. 4. As an article of manufacture, a homogeneous, molded elastic heel for boots and shoes, having a tread portion projecting from its face and a recess above said tread por- 10 15 20 25
- tion, to form an air-chamber when the heel is applied to the shoe.
5. As an article of manufacture, a homogeneous, molded elastic heel for boots and shoes, having a tread portion projecting from its face and a recess in its top, the body of the heel presenting a smooth and flat attaching-rib surrounding the recess.
- In testimony whereof I have signed my name to this specification in the presence of two subscribing witnesses.

WILHELM A. ZICKERMAN.
